BALUSTER OR SIMILAR ARTICLE

Andrew R. Checkwood, 2355 Montrose Ave., Montrose, Calif., and Andrew M. Checkwood, 7053 Greeley St., Tujunga, Calif.

Filed Aug. 2, 1965, Ser. No. 86,381

Term of patent 3½ years

(Cl. D13—7)

FIG. 1 is a perspective view of a baluster or similar article, showing our new design.

FIG. 2 is a top plan view, having reference to FIG. 1.
FIG. 3 is a bottom plan view having reference to FIG. 1, and

FIG. 4 is a transverse sectional view taken on the line 4—4 of FIG. 1.

We claim:

The ornamental design for a baluster or similar article, substantially as shown.
